UNITED STATES PATENT OFFICE.

GUSTAF ALBIN NILSON, OF GLENCOE, ILLINOIS.

SHOWER RECEPTOR.

Application filed July 19, 1926. Serial No. 123,374.

My invention relates to shower receptors and has for its object the provision of an improved receptor of this character which lends itself very readily into the construction of the completed shower bath structure in such a way that the water-tight characteristics of the structure remain permanently. My improved receptor is also of the character that it may be made of material which is not so slippery as that which has been heretofore frequently used for the flooring of shower baths.

My invention further contemplates the provision of a shower receptor of this kind which shall be a self-contained unitary element and which, in its preferred form, has the necessary means to accommodate the superposed structure in such a way that permanence of non-leaking characteristics of the structure may be maintained. I am aware that shower receptors have been made of enameled iron ware, but shower receptors of this character are so slippery in many cases as to be quite dangerous and are therefore, not as satisfactory as they should be. My invention is of such a nature that the means utilized in its execution are such as to prevent the difficulty referred to.

I will explain one form which my invention may take more in detail by referring to the accompanying drawings in which—

Fig. 1 is a front view partly in section of a structure constructed in accordance with my invention;

Fig. 2 is a sectional view on line 2—2 of Fig. 1;

Fig. 3 is a sectional view on line 3—3 of Fig. 1;

Fig. 4 is a sectional view on line 4—4 of Fig. 3;

Fig. 5 is an enlarged fragmentary sectional view along line 5—5 of Fig. 1; and

Fig. 6 is an enlarged fragmentary sectional view on line 3—3 of Fig. 1.

My improved shower bath structure comprises a shower receptor 10 which is made preferably of cementitious material such as cement or concrete and which is more or less pan-shaped as shown more clearly in Fig. 4. This receptor is provided with a drain opening into which the sleeve bushing 11 is placed which may have a perforated top 12 as shown more clearly in Fig. 4. The drain pipe 13 is mounted in this sleeve and is held in place so as to provide a waterproof joint through the agency of the lead

backing 14. The top surface of the receptor slopes toward the drain opening and the interior of this receptor is surrounded by a surrounding wall which, in the particular structure shown, consists of the wall portions 15, 16, 17 and 18. The receptor in this instance is shown as rectangular, but it is, of course, obvious that any suitable form will answer.

This receptor is made of a unitary self-contained piece of material such as that outlined, which is molded and which is suitably reinforced by reinforcing elements 19 as more clearly apparent from Fig. 4. The receptor when molded, is also molded so as to support a flange or ridge 20 which is preferably made of metal and which has the upper projecting portion 21 and the lower enclosed tail piece portion 22. The upper walls which are superposed on top of the receptor and which construction will be presently described, are mounted inwardly of this ridge portion 21 so that the drippings from these upper wall portions are directed inwardly toward the interior of the receptor.

My improved receptor may then be provided with any suitable flooring to harmonize with the building in design and finish and it may be of the mosaic type if desired. At any rate, being of the material of which it is made, it does not have the objectionable slipperiness which has heretofore been referred to. The receptor may be suitably placed wherever desired, and it may preferably be placed slightly below the floor level, the floor being indicated at 23. The ridge element 20 extends throughout the entire length of the wall portions 15, 16 and 17, but ends at the points marked 24 and 25 (Fig. 3) along the wall portion 18 so that the wall portion 18 practically constitutes an unobstructed sill portion for the shower bath structure.

There is superposed above the ridge element 20 and on top of the wall portions of the receptor preferably a surrounding metal sheathing 26 which extends throughout the entire length of the wall portions 15, 16 and 17, thus forming the U-shaped element and which extends inwardly over the wall portion 18 in the form of a projecting tongue 27. This enclosing sheathing 26 may extend as high as the shower bath structure as desired, for instance as high as the line 28 in Fig. 1 and it is preferably held in place by means of countersunk screws 29

such as shown more clearly in Fig. 4. In order to provide a suitable entrance casing for the shower bath structure, I utilize a preferably rectangular shaped metallic casing element 30 shown more clearly in Fig. 6 which has the walls 31, 32 and 33 and which has its remaining wall portions extend inwardly as at 34 having outward from thereon flaring portions such as the flaring portions 35 and 36. The tongue 27 enters between these two flaring portions and a circular clamping ring 37 slipped over the entire structure from the top and pressed downwardly in place clamps the elements 27, 35 and 36 tightly together.

The wall 33 at the bottom of the casing portion 30 extends lower than the remaining three wall portions, thus to form a downwardly extending cover plate 38 as shown more clearly in Fig. 5. The wall portion 34 at its lower point is slotted so as to permit it being mounted in place over the extending ridge element 20 which, as before stated, extends up to about the point 25 as more clearly shown in Figs. 5 and 6. The downwardly projecting apron 38 of the wall 33 is then preferably held in place by means of bolts 39, these being, if desired, of the expansion variety as shown so that they 30 may hold securely when embedded in the material of which the receptor 10 is made. It will thus be seen that the connection between the elements 26 and 20 is such that any water which may be splashed against 35 the sides upwardly of the receptor is directed to the interior of the receptor where it may be drained off through the drain pipe 13. If desired, the interior of the structure may be lined with marble or similar material such for instance as the marble slabs 40, 41 and 42. These marble slabs may also rest upon the receptor.

It is difficult, if not entirely impossible, to make secure joints between marble slabs so 45 that they remain waterproof especially when the building settles or when the building is subject to vibration as all buildings are and on this account the steel backing 26 become of considerable importance in maintaining 50 an absolutely waterproof surrounding for the shower bath structure. Suitable countersunk screws 43 may be employed to connect the walls 33 with the upwardly projecting ridge elements 21. The entire structure 55 may then be suitably enclosed by wall portions, as the wall portions 44, 45 and 46. A handle 47 may be provided in the interior of the device to control the water which issues from any suitably arranged spraying device 60 48. A curtain 49 may be suitably held from a pole 50 fastened between the side walls as shown. A cross-piece 51 may be provided to complete the structure as shown more clearly in Figs. 1 and 2.

From what has thus been shown and de-

scribed, the nature of my invention will be readily clear to those skilled in the art and it will also be understood that modifications may be made from the specific disclosure herein without departing from the spirit of 70 my invention.

Having thus described one form which my invention may take, what I claim as new and desire to secure by Letters Patent is:

1. A self-contained unitary base plate structure for shower baths and the like comprising a pan shaped element made of cement-like material having a smoothed exposed face and having a drain opening, and having its floor portion sloping toward said drain opening, and having upwardly extending side portions adapted to accommodate upwardly extending wall portions thereon, said side portions having a surrounding flange extending upwardly outside said wall portions to direct the drippings therefrom inwardly along said side portions.

2. A self-contained unitary base plate structure for shower baths and the like comprising a pan shaped element of cement like material having a drain opening and having its floor portion sloping toward said drain opening and having upwardly extending side portions provided with a narrow metal ridge, and a superposed enclosing metal wall mounted upon said side portions inwardly of said ridge, whereby the weight of the enclosing wall is supported on said side portions independently of said metal ridge.

3. A self-contained unitary base plate structure for shower baths and the like comprising a pan shaped element having a drain opening and having its floor portion sloping toward said drain opening and having upwardly extending side portions provided with a ridge, a superposed enclosing metal wall mounted upon said side portions inwardly of said ridge and a lining for said metal wall, said side portions having substantially flat top surfaces inwardly of said ridge whereby any liquid between said wall and lining will drain inwardly into said element.

4. A self-contained unitary base plate structure for shower baths and the like comprising a pan shaped element having a drain opening and having its floor portion sloping toward said drain opening and having upwardly extending side portions provided with a ridge element projecting upwardly from said side portions and having its lower portion countersunk therein and a superposed enclosing wall mounted upon said side portion inwardly of said ridge.

5. A self-contained unitary base plate structure for shower baths and the like comprising a pan shaped element having a drain opening and having its floor portion sloping toward said drain opening and having upwardly extending side portions provided

- with a ridge element projecting upwardly from said side portions and having its lower portion countersunk therein and a superposed enclosing wall mounted upon said side portion inwardly of said ridge and secured to said ridge.
6. A self-contained unitary base plate structure for shower baths and the like comprising a pan shaped element having a drain opening and having its floor portion sloping toward said drain opening and having upwardly extending side portions adapted to accommodate upwardly extending wall portions thereon and a metal surrounding ridge, the lower portion of which is countersunk within the material of said base plate and the upper portion of which projects upwardly therefrom.
7. A shower bath structure comprising a metal wall arranged to form the side portions of the structure and having opposing extremities separated to form an opening therebetween, two hollow metal casings, one for each side of said opening and into which the corresponding extremity of said wall portion projects, and means for clamping said casing to its corresponding projecting extremity of the wall portion.
8. A self contained unitary base plate structure for shower baths and the like comprising a pan shaped element of cement-like material having a drain opening and having its floor portion sloping toward said drain opening and having upwardly extending side portions, upwardly extending wall portions supported by said side portions, and a metal surrounding member countersunk within the material of said side portions and engaging said wall portions.
9. A shower bath structure comprising a metal wall arranged to form the side portions of the structure and having opposing extremities separated to form an opening therebetween, two casing members, one for each side of said opening, said casing members each having a vertically extending slot therein into which the corresponding extremity of said wall portion projects and means for securing each casing to its corre-
- sponding projecting extremity of the wall portion.
10. A self contained unitary base plate structure for shower baths and the like, comprising a pan shaped element made of cement-like material having a smooth exposed face and having a drain opening and having its floor portion sloping toward said drain opening, and having upwardly extending side portions adapted to accommodate upwardly extending wall portions thereon, said side portions having a surrounding flange extending upwardly outside said wall portions, said flange including means of different material than said base embedded in said cement-like material and adapted to have said wall portions secured thereto.
11. A self contained unitary base plate structure for shower baths and the like, comprising a pan shaped element made of cement-like material having a smooth exposed face, and having a drain opening and having its floor portion sloping toward said drain opening, and having upwardly extending side portions adapted to accommodate upwardly extending wall portions thereon, said side portions having a surrounding flange extending upwardly outside said wall portions, said flange including metallic means of different material than said base embedded in said cement-like material and adapted to have said wall portions secured thereto.
12. A self contained unitary base plate structure for shower baths and the like comprising a pan shaped element of cement-like material having a drain opening and having its floor portion sloping toward said drain opening and having upwardly extending side portions, upwardly extending wall portions supported by said side portions, and a surrounding ridge including means countersunk within said cement-like material, surrounding the lower edge of said wall portions and adapted to have said wall portions secured thereto.

In witness whereof, I hereunto subscribe my name this 16th day of June A. D., 1926.

GUSTAF ALBIN NILSON.
